UNITED STATES PATENT OFFICE.

JOHN E. SHAWHAN, OF NEVADA, MISSOURI.

SHOE.

No. 923,083.

Specification of Letters Patent.

Patented May 25, 1909.

Application filed October 9, 1908. Serial No. 456,863.

To all whom it may concern:

Be it known that I, JOHN E. SHAWHAN, a citizen of the United States, and a resident of Nevada, in the county of Vernon and State 5 of Missouri, have invented certain new and useful Improvements in Shoes, of which the following is a specification.

This invention is an improvement in shoes and particularly in the fastening devices of 10 the shoe and has for an object to provide a novel construction which will avoid the necessity of lacing the shoe down entirely to the base of the front opening, and will provide for preventing the gaping of the opening 15 below the laces by a construction which is conveniently secured in the shoe and held from twisting or other displacement; and the invention consists in certain novel constructions and combinations of parts as will 20 be hereinafter described and claimed.

In the drawing, Figure 1 is a front view of a blucher shoe, partly broken away and embodying my invention. Fig. 2 is a front view partly broken away, of an ordinary 25 form of lace shoe provided with my invention. Fig. 3 is a cross section on about line 3—3 of Fig. 1. Fig. 4 is a detail perspective view of the stiffening plate, and Fig. 5 is a front view, partly broken away, of a shoe 30 similar to that illustrated in Fig. 2, but showing the shoe opened instead of closed as in Fig. 2.

My invention is illustrated in connection with both a blucher form of shoe as shown in 35 Fig. 1, and the ordinary lace shoe as shown in Fig. 2, and as it possesses special advantages in connection with the blucher form of shoe having the flaps at the lower end of the front opening, I will first describe the invention in 40 connection with such form of shoe.

In the construction shown in Fig. 1, the shoe A has a front opening A', and the flaps A² at the lower end of the said opening, the upper portion of the shoe being supplied 45 along the front opening with hooks A³, and eyelets A⁴ and A⁵ being supplied below the hooks A³. The lower eyelets A⁵ operate in connection with the stiffening springs B, one of which is shown in detail in Fig. 4. It will 50 be understood that these springs, shown in Fig. 4, are made rights and lefts, may be made in different sizes and strength to adapt them for work shoes as well as for dress shoes, and may be made of any suitable material, preferably thin metal such as clock 55 spring metal and may be finished by nickel-

ing, japanning or otherwise in such manner as to avoid corrosion in use.

I form the spring with an intermediate or body portion B' with a lateral outwardly projecting wing B² at the upper end of the intermediate portion B', and with a lateral base wing B³ extending from the lower end of the intermediate portion laterally in the same general direction as the wing B² and curving 60 slightly upward toward its extremity B⁴ so it will not injure the shoe when the latter is opened as shown in Fig. 5. I also bend the lower end of the spring at B⁵ forwardly to prevent the same from pressing the sharp 65 edge against the foot of the wearer. The intermediate portion B' of the spring is bowed or arched slightly to the front as shown in Fig. 4, to conform to the arch of the instep, and the upper wing B² is provided with an 70 opening B⁶ which receives the lower eyelet A⁵, as will be understood from Figs. 1, 2 and 5 of the drawing, such eyelet operating to hold the spring securely in place, and co-operating with the lower lateral and upwardly curved 75 wing B³ in preventing any twisting or other displacement of the spring when the latter is applied to the shoe.

In operation the springs B are applied to the shoe between the upper leather and the 85 lining as best shown in Fig. 3, and are stitched in place, being thus firmly incased within the upper of the shoe and out of sight, the lateral perforated wing B² being firmly held by the eyelet A⁵ and the lower end of 90 the spring being braced in position by the lateral outwardly curved wing B³ as before described.

In operation the lace C may be applied as 95 shown in Fig. 1, and the shoe laced and fastened in the usual manner above the stiffening spring. Then when it is desired to remove the shoe it is only necessary to unlace the shoe down to the eyelets A⁴ when the shoe may be thrown wide open avoiding the 100 necessity of unlacing to the base of the front opening. At the same time when the shoe is laced and fastened as shown in Fig. 1, the stiffening plates, preferably of spring metal as described, will operate to hold the lower 105 portion of the front opening closed and prevent any gaping at such point.

When the invention is used on blucher shoes as shown in Fig. 1, a separate fastening such as a strap D and buckle as shown in 110 Fig. 1, is usually supplied to connect the opposite flaps A², and the special construction

of stiffening plate shown is of importance in the application of the invention to blucher shoes in that it stiffens the points of the flaps and tends to retain the same in the desired 5 flat shape.

I claim—

1. A shoe of the blucher type having a front opening and flaps at the lower end thereof, and provided with lacing hooks and 10 with eyelets below the same, and with a fastening device connecting the flaps at the lower end of the front opening of the shoe, and stiffening plates held in the uppers of the shoe on opposite sides of the said opening 15 and consisting of outwardly arched intermediate portions, laterally extending perforated wings at the upper ends thereof and receiving the lacing eyelets, and lateral outwardly extending wings at the lower ends of the said 20 intermediate portions and curving upwardly toward their free extremities, all substantially as and for the purposes set forth.
2. A shoe having a front opening and flaps at the lower end thereof, stiffening plates 25 held to the uppers adjacent to the marginal

edges of the front opening and provided at their lower ends with lateral outwardly extending wings, and at their upper portions with lateral outwardly extending wings perforated for the reception of eyelets, and eyelets applied through such openings, substantially as set forth. 30

3. A shoe having a front opening and provided with lacing hooks, and with eyelets below the same, and stiffening plates held to 35 the uppers of the shoe on opposite sides of the said opening, and consisting of outwardly arched intermediate portions, laterally extending perforated wings at the upper ends thereof and receiving lacing eyelets, and lateral outwardly extending wings at the lower ends of the said intermediate portions and curving upwardly toward their free extremities, substantially as and for the purposes set forth. 40

JOHN E. SHAWHAN.
